AWNING

Wilbert F. Volk, Fort Worth, Tex.

Application April 27, 1953, Serial No. 24,675

Term of patent 7 years

(Cl. D21—6)

To all whom it may concern:

Be it known that I, Wilbert F. Volk, a citizen of the United States, residing in Fort Worth, in the county of Tarrant and State of Texas, have invented a new, original, and ornamental Design for an Awning, of which the following is a specification, reference being had to the accompanying drawing, forming a part thereof.

Figure 1 is a perspective view of an awning, showing my new design.

Figure 2 is a side elevation, and

Figure 3 is a vertical sectional view.

The side of the awning not shown has substan-

tially the same appearance as the side shown in Figure 2.

I claim:

The ornamental design for an awning, substantially as shown and described.
